DESIGN FOR AN ORNAMENT FOR COSMETIC RECEPTACLES AND OTHER ARTICLES

William J. Reilly, Taunton, Mass.

Application December 10, 1945, Serial No. 124,586

Term of patent 14 years

(Cl. D86—10)

To all whom it may concern:

Be it known that I, William J. Reilly, a citizen of the United States, residing at Taunton, Massachusetts, have invented a new, original, and ornamental Design for an Ornament for Cosmetic Receptacles and Other Articles, of which the following is a specification, reference being had to the accompanying drawing, forming a part thereof.

In the accompanying drawing:

Figure 1 is a plan view of an ornament for cosmetic receptacles and other articles, showing my design;

I claim:

The ornamental design for an ornament for cosmetic receptacles and other articles, substantially as shown.

WILLIAM J. REILLY.
